UNITED STATES PATENT OFFICE.

JOSEPH HARRISON FRENCH, OF PETERBORO, ONTARIO, CANADA.

DENTAL CASTING MACHINE.

1,460,044.

Specification of Letters Patent. Patented Dec. 13, 1921.

Application filed February 24, 1921. Serial No. 447,579.

To all whom it may concern:

Be it known that I, JOSEPH HARRISON FRENCH, of the city of Peterboro, in the county of Peterboro, in the Province of Ontario, Canada, have invented certain new and useful Improvements in Dental Casting-Machines, of which the following is the specification.

My invention relates to improvements in dental casting machines and the object of the invention is to devise a simple, cheap and effective apparatus for casting dental fillings which will always be set up ready for use. A further object is to construct an apparatus in which the sealing member for the mold casing will press down uniformly on the same. A still further object is to devise a dental casting machine which will cast from the smallest inlay casting to a plate. Another object is to devise a simple and effective control air valve for the apparatus and another object is to provide means whereby mold casings of different diameters may be conveniently held in place in the apparatus. Another object is to construct a machine in which the entire working mechanism will be carried on a swingable bracket which is limited to a definite forward and backward movement.

My invention consists of a dental casting machine constructed and arranged all as hereinafter more particularly described and illustrated in the accompanying drawing in which:

Figure 1 represents a side elevation of my machine.

Fig. 2 is a vertical section through the control valve showing the same in the closed position.

Fig. 3 is a similar view to Fig. 2, but reversed thereto, and

Fig. 4 is a plan view of the base of the apparatus showing the means for holding mold casings of different diameters in place.

Fig. 5 is a vertical section showing the device applied to a mold casing and inlay mold.

Like characters of reference indicate corresponding parts in the different views:

1 is the base plate of the machine provided with the lugs 2. Screws may be passed through the lugs 2 to hold the machine firmly on a suitable supporting structure. 3 are suitably spaced lugs extending upwardly from the base plate 1 in the vicinity of one end thereof. 4 is a swingable bracket suit-

ably pivoted at its lower end by the pin 5 between the lugs 3, said bracket being provided with a foot 6 carrying a screw 7 provided with the lock nut 8, the lower end of the screw 7 being adapted to engage the upper face of the base plate 1. 9 is a hollow boss formed on the bracket 4 and constituting the bearing for the plunger 10 which is 60 65

slidable therein. 11 is an arm extending upwardly from the bracket 4 and preferably formed integrally therewith. 12 is a lever pivotally connected to the arm 11 by the pin 13 which extends through one of the holes 14 in such arm. 15 is the air valve casing suitably secured to the lower end of the plunger 10 and having a laterally extending hollow boss 16. 70

The lower end of the plunger 10 has a central aperture extending up thereto a certain extent and adapted to receive the valve stem 17, said valve stem being provided with a flattened face 18 and an opposed slot 19 adapted to receive the inner end of the set-screw 20. 21 is a cross orifice extending into 75 80 the interior of the stem from the flattened surface thereof and communicating with a vertical orifice 22 extending to the bottom of the stem. 23 and 24 are plates suitably secured to the valve stem 17, and 25 is a 85 gasket of resilient material below said plates also secured to the stem 17 by the flat nut 26. 27 are clips adapted to hold the outer periphery of the gasket 25 to the plates 24, in order that the gasket 25 will seal properly, 90 as will hereinafter appear.

28 is a tubular valve member of resilient material provided with a suitable split cover 29, said valve member being situated in the hollow interior of the boss 16 of the valve 95 casing. 30 is a hose nipple adapted to be screwed into the outer end of the hollow boss 16, the inner end of the nipple engaging the outer end of the valve member. 31 is a hose connecting the nipple 30 with an air compression cylinder 32. 33 is a piston in said cylinder having the upwardly extending stem 34 provided at its upper end with the weight 35. 100

36 is a plate preferably formed integrally with the base plate 1 upon which the mold casing 37 is adapted to rest. 38 are studs adapted to center the largest mold casing 41. 40 are removable studs adapted to center the mold casing 37, said studs being capable of being removed and inserted into the holes 110 42 and thus center the smaller mold casing 43. 45 is a spring interposed between the top

of the central aperture 44 above referred to and normally holding the valve stem in the position shown in Fig. 2 with the valve closed.

- 5 48 is an inlay mold of plaster of Paris or other suitable material and provided at its upper end with a concavity 49 from which extends a channel 50 leading to the cavity 51 which corresponds in shape to the dental 10 casting.

The machine is used as follows:

- The molten gold or other metal is poured 15 into the mold 48 within the casing 43 and to facilitate this operation the bracket 4 is swung back about the pin 5 until the pin 46 comes into engagement with the top of the lug 3. Thus when the bracket is swung back the mold and the gold is perfectly visible so that the metal during the process of heating 20 can be closely observed until the proper fluidity for casting is obtained, the operator being able to stand in the normal upright position.

It is to be understood that the metal is 25 preferably preheated to just below fluid state on a block of charcoal or crucible with an oxy-acetylene or oxy-hydrogen torch. The metal is then transferred to the mold 49 by pincers or other suitable means. The heat is 30 then continued by said torch until the proper fluid state is reached.

The weight 35 and the attached piston rod and piston 33 is then pulled up the required extent in the air compression cylinder 32. In 35 this position the air valve will be closed.

The handle of the lever 12 is now grasped by the operator and the bracket 4 is swung over until the plunger 10, the plates 23 and 24 and the attached gasket 25 are immediately 40 above the mold casing 43, which is centered by the respective pins depending on the size of mold casing used.

The lever 12 is now pressed downwardly which causes the plunger 10 and the attached 45 valve casing and gasket 25 to be pressed down until the gasket comes into engagement with the lip of the mold casing 43, thus forming an effective seal.

By pressing the lever 12 down a further 50 extent it will be seen that as the valve stem 17 attached to the plates 23 and 24 and gasket 25 will not be permitted to move down a further extent, therefore the valve casing 15 will be moved down by the plunger 10 relatively to the valve stem, thus compressing the spring 45 in the aperture 44. When the lever 12 is down the full extent the longitudinal orifice 47 in the valve member 28 will register with the cross aperture 21 in the 55 valve stem. Consequently air will be forced from the air compression cylinder 32, through the hose 31, through the nipple 30, orifice 47 in the resilient valve member, through the horizontal orifice 21 and vertical orifice 22 in the valve stem and finally force

the metal down through the channel 50 into the cavity 51 of the mold and forcing such gold or other metal against the walls of such cavity in the mold the cavity being of the exact size and shape of the desired casting. 70

Pressure is maintained until the gold is cold when the bracket 4 may be swung back and the mold casing 43 removed.

Should the valve member 28 leak through wear it is only necessary to tighten up the 75 nipple 30 which abuts such valve member in order to press the same firmly against the flattened surface 18 of the valve stem. The setscrew 20 is provided for preventing the turning of the valve stem relatively to the 80 valve casing 15 and the plunger 10, but owing to such setscrew being inserted into the vertical slot 19 the valve stem is permitted the vertical movement referred to above.

From the above description it will be seen 85 that I have devised a simple and effective dental casting machine in which the pressure on the gasket 25 will be vertical and consequently the pressure on the upper lip of the mold casing 43 will be uniform.

In addition I have devised a simple and effective air valve therefor which will be positive in action and which can be readily adjusted due to wear.

What I claim as my invention is.

1. In a dental casting machine, the combination with the base plate and a hinged bracket thereon, of a mold detachably mounted on the said base plate, a mold cover, a vertical plunger slidably mounted 100 on the hinged bracket, said vertical plunger having an orifice extending up from the bottom thereof, a valve casing mounted on the lower end of the said plunger, a valve stem secured at its lower end to the mold 105 cover and extending up through the valve casing into the orifice in the plunger, said valve stem having a vertical orifice extending up therethrough for a certain extent and communicating with a horizontal 110 orifice opening in the side of the stem, a spring interposed between the top of the valve stem and the top of the orifice in the plunger, means for preventing the rotation of the valve stem relatively to the 115 plunger and valve casing, a valve member adapted to engage the valve stem, and means for admitting air through the valve member and through the valve stem, and through the mold cover into the mold upon 120 the horizontal orifice in the valve stem registering with the corresponding orifice in the valve member.

2. In a dental casting machine, the combination with the base plate and a hinged 125 bracket thereon, of a mold detachably mounted on the said base plate, a mold cover, a vertical plunger slidably mounted on the hinged bracket, said vertical plunger having an orifice extending up from the bot- 130

tom thereof, a valve casing mounted on the lower end of the said plunger, a valve stem secured at its lower end to the mold cover and extending up through the valve casing 5 into the orifice in the plunger, said valve stem having a vertical orifice extending up therethrough for a certain extent and communicating with a horizontal orifice opening in the side of the stem, a spring interposed between the top of the valve stem and the top 10 of the orifice in the plunger, means for preventing the rotation of the valve stem relatively to the plunger and valve casing, a valve member adapted to engage the valve stem, a vertical air cylinder, a weighted piston fitting the cylinder and adapted to create 15 air pressure therein, a hose connecting the bottom of the cylinder with the valve casing for admitting air under pressure through the valve member into the valve stem and through 20 the valve member into the mold cover into the mold upon the horizontal orifice in the valve stem registering with the corresponding orifice in the valve member 25 3. In a dental casting machine, the combination with the base plate and a hinged bracket thereon, of a mold detachably mounted on the said base plate, a mold cover, a vertical plunger slidably mounted 30 on the hinged bracket, said vertical plunger having an orifice extending up from the bottom thereof, a valve casing mounted on the lower end of the said plunger, a valve stem secured at its lower end to the mold 35 cover and extending up through the valve casing into the orifice in the plunger, said valve stem having a vertical orifice extending up therethrough for a certain extent and communicating with a horizontal orifice 40 opening in the side of the stem, a spring interposed between the top of the valve stem and the top of the orifice in the plunger, means for preventing the rotation of the valve stem relatively to the plunger and 45 valve casing, a valve member adapted to engage the valve stem, a vertical air cylinder, a weighted piston fitting the cylinder and adapted to create air pressure therein, a hose connecting the bottom of the cylinder with the valve casing 50 with the valve casing for admitting air under pressure through the valve member into the valve stem and through the mold cover into the mold upon the horizontal orifice in the valve stem registering with the corresponding orifice in the valve member and means for moving the vertical plunger in a 55 downward direction. 4. In a dental casting machine, the combination with the base plate and a hinged bracket thereon, of a mold detachably mounted 60 on the said base plate, a mold cover, a vertical plunger slidably mounted on the hinged bracket, said vertical plunger having an orifice extending up from the bottom 65 thereof, a valve casing mounted on the lower end of the said plunger, a valve stem secured at its lower end to the mold cover and extending up through the valve casing into the orifice in the plunger, said valve stem having a vertical orifice extending up therethrough for a certain extent and communicating with a horizontal orifice opening in the side of the stem, a spring interposed between the top of the valve stem and the top 70 of the orifice in the plunger, means for preventing the rotation of the valve stem relatively to the plunger and valve casing, a valve member adapted to engage the valve stem, a vertical air cylinder, a weighted piston fitting the cylinder and adapted to create 75 air pressure therein, a hose connecting the bottom of the cylinder with the valve casing for admitting air under pressure through the valve member into the valve stem and through the mold cover into the mold upon the horizontal orifice in the valve stem registering with the corresponding orifice in the valve member, said hinged bracket having an upwardly extending arm, a lever fulcrumed on 80 said arm and pivotally connected intermediate of its length to the upper end of the vertical plunger. 5. In a dental casting machine, the combination with the base plate and bracket hinged thereto, of a vertical plunger slidably mounted on the bracket, said vertical plunger having an orifice extending up a certain extent from its lower end, a mold cover, a resilient gasket on the lower face of the mold cover, a valve stem secured to the mold cover and adapted to extend up through the valve casing into the orifice in the plunger, a spring interposed between the top of the valve stem and the top of the orifice, said valve stem having a vertical orifice extending 85 up from its lower end and communicating with a horizontal orifice and communicating with the outside of the valve stem, a setscrew extending through the valve casing adapted to engage a vertical slot in the valve stem, one side of the valve stem being flattened, a resilient valve member having a central orifice extending therethrough, the inner end of the resilient valve member adapted to engage the flattened surface of the valve stem, a nipple adapted to engage the outer end of the valve member and capable of being adjusted to hold the valve member in engagement with the valve stem. 100 6. In a dental casting machine, the combination with the base plate and bracket hinged thereto, of a vertical plunger slidably mounted on the bracket, said vertical plunger having an orifice extending up a certain extent from its lower end, a mold cover, a resilient gasket on the lower face of the mold cover, a valve stem secured to the mold cover and adapted to extend up through the valve casing into the orifice in the plunger, a spring interposed between the top of the valve stem and the top of the orifice, said valve stem having a vertical orifice extending up from its lower end and communicating with a horizontal orifice and communicating with the outside of the valve stem, a setscrew extending through the valve casing adapted to engage a vertical slot in the valve stem, one side of the valve stem being flattened, a resilient valve member having a central orifice extending therethrough, the inner end of the resilient valve member adapted to engage the flattened surface of the valve stem, a nipple adapted to engage the outer end of the valve member and capable of being adjusted to hold the valve member in engagement with the valve stem. 115 7. In a dental casting machine, the combination with the base plate and bracket hinged thereto, of a vertical plunger slidably mounted on the bracket, said vertical plunger having an orifice extending up a certain extent from its lower end, a mold cover, a resilient gasket on the lower face of the mold cover, a valve stem secured to the mold cover and adapted to extend up through the valve casing into the orifice in the plunger, a spring interposed between the top of the valve stem and the top of the orifice, said valve stem having a vertical orifice extending up from its lower end and communicating with a horizontal orifice and communicating with the outside of the valve stem, a setscrew extending through the valve casing adapted to engage a vertical slot in the valve stem, one side of the valve stem being flattened, a resilient valve member having a central orifice extending therethrough, the inner end of the resilient valve member adapted to engage the flattened surface of the valve stem, a nipple adapted to engage the outer end of the valve member and capable of being adjusted to hold the valve member in engagement with the valve stem. 120 8. In a dental casting machine, the combination with the base plate and bracket hinged thereto, of a vertical plunger slidably mounted on the bracket, said vertical plunger having an orifice extending up a certain extent from its lower end, a mold cover, a resilient gasket on the lower face of the mold cover, a valve stem secured to the mold cover and adapted to extend up through the valve casing into the orifice in the plunger, a spring interposed between the top of the valve stem and the top of the orifice, said valve stem having a vertical orifice extending up from its lower end and communicating with a horizontal orifice and communicating with the outside of the valve stem, a setscrew extending through the valve casing adapted to engage a vertical slot in the valve stem, one side of the valve stem being flattened, a resilient valve member having a central orifice extending therethrough, the inner end of the resilient valve member adapted to engage the flattened surface of the valve stem, a nipple adapted to engage the outer end of the valve member and capable of being adjusted to hold the valve member in engagement with the valve stem. 130

valve stem and the top of the orifice, said valve stem having a vertical orifice extending up from its lower end and communicating with a horizontal orifice and communicating with the outside of the valve stem, a setscrew extending through the valve casting adapted to engage a vertical slot in the valve stem, one side of the valve stem being flattened, a resilient valve member having a central orifice extending therethrough, the inner end of the resilient valve member adapted to engage the flattened surface of the valve stem, a nipple adapted to engage the outer end of the valve member and capable of being adjusted to hold the valve member in engagement with the valve stem, a foot on the hinged bracket, a setscrew ex-

tending through said foot and provided with a lock nut, the lower end of the screw engaging the base plate for limiting the inward movement of the hinged bracket and a pin on the side of the bracket for limiting its outward movement. 20

7. In a dental casting machine, the combination with the different sized circular molds and a base plate having a plurality of suitably spaced concentric holes in the upper surface thereof, said holes being situated in different radii corresponding with the radii of the different molds, of a plurality of pins 25 inserted into any selected set of holes for holding the corresponding mold in its centered position. 30

JOSEPH HARRISON FRENCH.
